UNITED STATES PATENT OFFICE.

JALMER NELSON AND GLENN M. RING, OF WHITETAIL, MONTANA.

CLOTHES TONGS.

Application filed September 29, 1922. Serial No. 591,326.

To all whom it may concern:

Be it known that we, JALMER NELSON and GLENN M. RING, citizens of the United States, residing at Whitetail, in the county of Sheridan and State of Montana, have invented certain new and useful Improvements in Clothes Tongs, of which the following is a specification.

Our invention relates to improvements in clothes tongs.

An object of our invention is to provide a clothes tong, especially useful in removing clothes from a tub containing hot or cold water, so as to obviate the danger of injuring the hands.

A further object of our invention is to provide a clothes tong, that will take the place of the old meat forks, sticks, or stove pokers, which have been commonly used heretofore, and which invariably tear the clothes.

A still further object of our invention is to provide a clothes tong, which can be used for large clothes as well as small, where it is desired to remove the same from a tub, boiler or washing machine.

A still further object of our invention is to provide a clothes tong, which may be used in conjunction with a vacuum washer.

A still further object of our invention is to provide a clothes tong, which is strong, durable, simple and inexpensive in construction, and which is well adapted to the use for which it is designed.

Other objects and advantages of the invention will become apparent during the course of the following description.

In the accompanying drawings forming a part of the specification and in which like numerals are employed to designate like parts throughout the same,

Figure 1 is a perspective view of the device embodying our invention,

Figure 2 is a section taken on line 2—2 of Figure 1, looking in the direction of the arrow,

Figure 3 is a section taken on line 3—3 of Figure 1 looking in the direction of the arrow, and

Figure 4 is a detailed perspective of the gripping attachment which is mounted on the front handle of our invention.

In the drawings, wherein for the purpose of illustration is shown a preferred embodiment of our invention, the numerals 5 and 6 designate a pair of jaws, which are of a

curved structure being provided with the corrugated engaging faces 7. The jaw 5 is carried by the longer shank or handle 8 while the jaw 6 is carried by the shorter shank or handle 9. A fulcrum bracket includes a body 10 adapted to fit about the intermediate portion of the shank or handle 8 and the legs 11 are provided for pivotally mounting the handles 8 and 9 in relation to each other. A shaft 12 is disposed between the two legs of the bracket 10 which forms a seat for a spring, 13, to facilitate in returning the shank 9 to its original position.

A flattened sleeve 14 is mounted on the shorter shank 9 between the legs 11 of the bracket 10, said shank 9 being pivoted by means of a bolt 15 passing through the legs 11 the flattened sleeve 14 and the shorter shank 9. It will be seen that the spring 13 is provided with the extensions 15' and 16, the extension 15' bearing against the longer shank 8 and the extension 16 bearing against the shorter shank 9. The action of the spring will have a tendency to keep the jaws closed.

A handle 17 is mounted on the end of the shank 9 and includes an extension 18 which diverges from the shank 8 so that the device may be more easily operated. By pressing inwardly from the extension 18 the jaws 5 and 6 may be separated from each other and allowed to engage the clothes in the hot or cold water, whereby they may be readily removed without any danger of the clothes becoming torn or without the necessity of the operator putting his hands in the water. It will also be noted that the device is just as useful with small articles as with large articles. A connection 19 is mounted on the end of the shank 8, so that the tong may be used in conjunction with a vacuum washer.

It will be seen that with ordinary clothes the tension of the spring holds the jaws tight enough to prevent the same from sliding off. Where a larger article such as a blanket is to be taken out of the water or handle it can be wound around the tong and made easier to handle. Where smaller articles are used it is only necessary to use the tongs in one hand, as the tension of the spring will close the jaws tight. However, when a larger article is to be manipulated, it is advisable that both hands be used, although it is not necessary. One of the important features of the invention is the flattened sleeve 14, which will prevent the wood of

the shank 9 from becoming swollen, thereby making the shank stick between the legs 11 and causing a great deal of inconvenience to the operator.

6. It is thought that the operation and construction of the invention will be readily understood without a more detailed description thereof, but it is designed to point out that the present embodiment of the invention has merely been disclosed by way of example and that numerous changes in the details of construction and the combination and arrangement of parts may be resorted to without departing from the spirit 10 of the invention or the scope of the subjoined claims.

Having thus described our invention, we claim:—

1. A clothes tong of the class described 20 including a pair of shanks of different lengths, a fulcrum bracket including a body disposed about one of the shanks and fixed thereto, a pair of plates extending from the body, means for pivoting the other shank 25 in engagement with said plates, jaws provided on said shanks and means co-operat-

ing with the fulcrum bracket for normally holding said jaws in engagement with each other.

2. A clothes tong of the class described 30 including a pair of shanks one longer than the other, a fulcrum bracket including a body disposed about one of the shanks, a pair of plates extending from the body, a shaft disposed between the plates intermediate their ends, a flattened sleeve disposed about the other shank adapted to be received between said plates, means for pivoting said sleeve to said plates, a spring disposed about the shaft, and being provided 35 with extensions to engage said shanks for normally holding the outer ends thereof in abutment with each other, said ends being formed with gripping jaws.

In testimony whereof we affix our signatures in presence of two witnesses.

JALMER NELSON.
